US0D1109594S

(12) **United States Design Patent** (10) **Patent No.:** **US D1,109,594 S**
(45) **Date of Patent:** **** Jan. 20, 2026**

(54) **PART OF A FURNITURE FITTING**

(71) Applicant: **Julius Blum GmbH**, Hoechst (AT)
(72) Inventor: **Sarah Scheffknecht**, Krumbach (AT)
(73) Assignee: **JULIUS BLUM GMBH**, Hoechst (AT)

(**) Term: **15 Years**

(21) Appl. No.: **29/883,043**

(22) Filed: **Jan. 23, 2023**

(30) **Foreign Application Priority Data**

Jul. 25, 2022 (EM) 9097108
(51) **LOC (15) Cl.** **08-08**
(52) **U.S. Cl.** USPC **D8/382**

(57) **CLAIM**

The ornamental design for a part of a furniture fitting as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of a part of a furniture fitting;

FIG. 2 is a front view thereof;

FIG. 3 is a right side view thereof;

FIG. 4 is a left side view thereof;

FIG. 5 is a rear view thereof;

FIG. 6 is a bottom view thereof;

FIG. 7 is a top view thereof;

FIG. 8 is a perspective view of a second embodiment of a part of a furniture fitting;

FIG. 9 is a front view thereof;

FIG. 10 is a rear view thereof;

FIG. 11 is a bottom view thereof;

FIG. 12 is a top view thereof;

FIG. 13 is a right side view thereof; and,

FIG. 14 is a left side view thereof.
